(57) **CLAIM**

The ornamental design for a laser apparatus, as shown and described.

DESCRIPTION

FIG. 1 is a perspective view of the laser apparatus in accordance with the present invention;

FIG. 2 is a front elevational view of the laser apparatus of FIG. 1;

FIG. 3 is a top view of the laser apparatus of FIG. 1;

FIG. 4 is a left elevational side view of the laser apparatus of FIG. 1;

FIG. 5 is a right elevational side view of the laser apparatus of FIG. 1;

FIG. 6 is a rear elevational view of the laser apparatus of FIG. 1; and,

FIG. 7 is a cross sectional view along line 7—7 in FIG. 2.

The broken lines in the drawings illustrate environmental material that forms no part of the claimed design.
